THOMAS SHIPLEY, OF YORK, PENNSYLVANIA.

REFRIGERATING OR ICE-MAKING APPARATUS.

1,325,211.

Specification of Letters Patent. Patented Dec. 16, 1919.

Application filed May 24, 1919. Serial No. 299,420.

To all whom it may concern:

Be it known that I, THOMAS SHIPLEY, a citizen of the United States, residing at York, in the county of York and State of Pennsylvania, have invented certain new and useful Improvements in Refrigerating or Ice-Making Apparatus, of which the following is a specification.

My invention relates to a refrigerating or ice making system or apparatus of the compression type, in which the ammonia, or other refrigerant fluid, circulates in a closed circuit including a compressor, a condenser, a receiver, and an evaporator where- 10 in the effective or useful work is done, the refrigerant passing from the discharge side of the compressor successively to and through the condenser, the receiver, the evaporator, and thence back to the compressor on the suction side of the same. Plants of this character are usually designed with reference to a certain normal rate of 15 production, say 100 tons refrigeration or ice making, or what not, per diem, and the different members of the plant are designed with a view to effecting that result with the greatest practicable efficiency and economy.

Not infrequently however it becomes desirable to run plants of this type at times 20 or for a season at less than normal or full capacity. In such cases a considerable increase of horse power per ton of refrigeration or ice making takes place if the speed of the compressor remains the same. In 25 these circumstances the volume of gas handled remains the same while the work being done is lessened, and this results in lowering the pressure of the gas—the back pressure or suction pressure so-called—and 30 corresponding temperature on the evaporating side of the system, and consequently in requiring a corresponding increase of horse power per ton of work done to compress the gas in the process of liquefying it.

It has long been known that, on such occasions, the normal suction pressure could be maintained, and even increased, by reducing the speed of the compressor; and in cases where the means for operating the 35 compressor were such (steam engines for example) that its speed could be economically reduced in proportion to the reduction in the work to be done, the advantage of operating at the highest possible suction pressure could be utilized.

But other means,—gas and oil engines and

electric motors—for operating the compressor, which have comparatively recently come into extensive use as a power for such purpose, were not such that the speed of the compressor could be economically reduced proportionately to the reduction in the work to be done, and the many efforts which have been made to provide them with means for speed regulation to meet the fluctuations of power required, have met with only partial success, at the best. In the case of variable speed electric motors, speed regulation of the compressor can be accomplished, but not with an accompanying reduction in the use of current; in the case of gas and oil engines, it can be accomplished to a very limited and unsatisfactory extent only.

In addition to the loss in economy experienced on such occasions, there are other serious disadvantages encountered when the relation between the work to be done and the speed at which the compressor must run is such that the resulting suction pressure and its corresponding temperature are very low; not infrequently this temperature becomes so low that the cooling water in the jackets of the compressor cylinders freezes and bursts the cylinders and their jackets, and, when the compressor happens to be of the now popular inclosed type containing in its inclosing case or housing the oil for the lubrication of its working parts by what is known as the splash system, the oil congeals and does not lubricate the said parts effectively, which results in their heating and scoring and sometimes breaking.

The object of my invention is to provide means whereby all devices for speed regulation of the compressor—at present known or used—may be profitably dispensed with, and the suction pressure may be varied at will to conform to fluctuations in the work to be done, while the speed of the compressor remains constant, thus permitting the plant to operate at all times to the best advantage.

To this end my invention may be stated to consist in a closed refrigeration or ice making system of the compressor type hereinbefore specified in which the compressor is associated with an auxiliary clearance chamber communicating with the interior of the compressor cylinder on the compression side of the piston therein, and provided with means by which the volumetric capacity of, or in other words the clearance in, said

chamber, and consequently the clearance in the compressor as a whole, may be increased or decreased, whereby, without changing the speed of the compressor, its capacity can be 5 so regulated as to vary at will the pressure on the suction side of the piston to conform to the fluctuations in the work to be done.

Under normal conditions communication 10 between the clearance chamber and compressor cylinder is closed. When, however, communication between them is opened, the gas taken in by the compressor on the suction stroke enters and fills the clearance chamber also, and is compressed therein on 15 the return or compression stroke of the piston. The gas thus admitted to this chamber re-expands on each suction stroke of the piston and thereby correspondingly reduces the volume of the incoming gas from the 20 suction side on such stroke, and this in turn correspondingly raises the pressure on the suction or evaporating side of the system. By providing means whereby, while the 25 compressor is in operation, the volumetric capacity of the clearance chamber can be varied at will to regulate the amount of gas admitted to it from the cylinder, the plant can at all times be run under the back pressure best suited for the work to be done.

30 Obviously the effect of the use of the clearance chamber will be a reduced percentage of the volumetric capacity of the compressor, but the loss will be so much more than compensated by the higher back 35 pressure obtained that the net result will be a less horse power per ton for the lesser work on such occasions than for the greater work when running at full capacity.

To enable others to better understand and 40 use my invention I will now proceed to describe more in detail the manner in which it is or may be carried into effect by reference to the accompanying drawings, forming part of this specification, in which—

45 Figure 1 is a representation largely diagrammatic of an apparatus embodying my invention in its preferred form.

Fig. 2 is an axial section on an enlarged 50 scale of so much of a single acting vertical compressor machine with my improvement applied thereto, as needed for the purpose of explanation.

Fig. 3 is an axial section on still larger 55 scale of a portion of the clearance chamber and the devices for controlling communication between it and the compression cylinder, as well as for varying its volumetric capacity.

Confining attention to Fig. 1, C is the 60 condenser in which the compressed ammonia gas, led through pipe 4 from the high pressure or discharge side of the constant speed single acting compressor D (of any usual or suitable type), is liquefied; A is the receiver 65 into which the liquefied ammonia

is discharged from the condenser through pipe 1; E is the evaporator in which the useful work is done, and which draws its supply of liquid ammonia for this purpose from the receiver A through pipe 2 and 70 returns it in the form of gas to the low pressure or suction side of the compressor D through pipe 3, to be again compressed and returned to the condenser, thus completing the cycle. The auxiliary clearance chamber 75 hereinbefore referred to is shown as a cylinder F mounted on the discharge end of the compressor cylinder and communicating with the interior of the same on the compression side of the piston therein. The means 80 for regulating the volumetric capacity of the auxiliary clearance chamber are typified by a piston G, and a screw threaded piston rod H extending through and engaging a screw threaded hole in the head of the clearance 85 chamber and provided with a handle I by which it may be manually operated to move the piston longitudinally of the cylindrical clearance chamber to vary its volumetric capacity. When the plant is running at its full, 90 or normal, capacity, communication between the clearance chamber and compression cylinder is closed as represented in the figure wherein the piston G is shown in position to cut off the clearance chamber entirely from 95 the compressor cylinder. If however the amount of work to be done is for any reason reduced below the full per diem capacity for which the plant is designed, the piston G, by means of its screw stem H and handle 100 I, is moved to open wide the auxiliary clearance chamber to the admission of gas from the compressor cylinder, and is so adjusted as to regulate the space available for that 105 purpose within the auxiliary clearance chamber, or in other words the clearance in said chamber, and consequently the clearance in the compressor as a whole, as required to produce and maintain the back, or suction, pressure best suited for the work to be done. 110 The gas thus admitted to the adjustable clearance chamber from the compressor cylinder re-expands on each suction stroke of the compressor piston, and thereby limits the amount of incoming gas on such stroke, 115 and this in turn raises the suction or back pressure with the resulting net economical gain in less horse power per ton for the lesser work than is required for the greater work when running at full capacity as hereinbefore explained. A valve controlled 120 pipe connection 5 between the high pressure side of the system and the head of the clearance chamber above the piston therein can be provided to balance the pressure on 125 the clearance chamber piston G when an adjustment of the clearance in said chamber is needed.

The structural details of the clearance device, and the manner of applying it to the 130

compressor cylinder can, without departure from my invention, be widely varied, depending upon the type of compressor with which it is to be associated and other mechanical and structural considerations. In Figs. 2 and 3, I have represented its preferred form of embodiment when associated with a single acting vertical machine.

In these figures D is a vertical compressor cylinder; 6 the discharge outlet from the cylinder; 7 the suction inlet to the cylinder; J the reciprocating compressor piston; DV the discharge valve in the safety head of the cylinder; SV the suction valve in piston J. 10 These parts may be of any usual or suitable construction; and their mode of operation and the manner in which they are as a whole connected up in the closed ammonia circulating system of Fig. 1 will be understood 15 without further explanation.

F is the cylindrical auxiliary clearance chamber suitably secured to, and projecting laterally, in horizontal position from, the side of the vertical compressor cylinder, and 20 communicating with the interior of the said compressor cylinder through a tubular stem S, secured at its outer end in a tubular passage 9 formed in the base of the clearance chamber and extending therethrough to the 25 interior of the latter, and at its inner end entering and fitting an opening formed in the side of the compressor cylinder a little below the safety head T, the said tubular stem serving to put the clearance chamber in communication with the interior of the compressor cylinder on the compression side of the piston. The clearance regulating piston G fits the interior of the clearance chamber closely and it is provided with suitable 30 packing to make a tight joint between the two. The front portion of the piston, in this instance, is preferably of frusto-conical shape as shown and in closed position fits closely against the adjoining head of the 35 clearance chamber which is correspondingly recessed to receive it. L is the tubular piston adjusting rod which extends out through a stuffing box M on the outer head of the clearance chamber, and thence extends 40 through a rotary internally screw threaded regulating nut N which is mounted to rotate without longitudinal movement in a suitable bearing on the outer end of the stand O cast in one with or otherwise suitably secured to the outer head of the clearance chamber. The rod L is externally screw threaded to engage the nut N and is provided with an operating wheel W on its outer end, by which the piston can be 45 adjusted to regulate the clearance in the auxiliary chamber as desired, or indeed to exclude the gas entirely from the chamber. I prefer however to employ for the last named purpose a separate and independently movable and operable stop plug R for closing the

clearance port in the side of the compressor cylinder through which the tubular stem S communicates with the interior of said cylinder. The stem S, the clearance piston rod L for a portion of its length and the opening in the clearance piston between the two are all of the same internal diameter and in axial alignment with one another, and the stop plug R is of such diameter as to fit closely but slidably therein. The stop plug 70 has a spline and groove connection 10 with the tubular regulating rod L to permit it to move lengthwise therein without rotation. For the purpose of operating the stop plug I provide a stem S, the screw threaded front portion of which enters the plug and engages a correspondingly internal screw thread formed in the rear end of the tubular portion of the stop plug which is slightly internally contracted for that purpose as 80 shown. The stem S extends rearwardly and axially through the tubular clearance piston rod L, the internal diameter of the rear portion of the said rod being reduced so that it shall fit closely, and furnish a bearing for, 85 the plug operating stem. Said stem passes out through a stuffing box M' on the rear end of the tubular clearance piston rod and is provided with suitable means for permitting it to rotate without longitudinal movement—in this instance an annular collar on it which is confined in the stuffing box M' as shown. On its rear end the stem is provided with an operating handle X by which the stop plug can be operated to open and close the port which it controls as desired. 90

While, with careful workmanship, the clearance piston can be made to fit so closely against the inner cylindrical surface of the clearance chamber as to prevent any gas 105 from passing through to the space in rear of the piston, thus permitting a valve controlled communication 5 directly between the clearance chamber and the high pressure side of the system, as illustrated in Fig. 1, 110 yet, as a precautionary measure, I prefer to employ additional means for effectually preventing this occurrence. To this end in the present instance I make use of an oil reservoir T' having a funnel and hand valve-controlled connection V' through which the reservoir may be supplied with oil; a hand valve-controlled oil-supply connection V² between the reservoir and the outer end of the clearance chamber; a hand valve-controlled connection V³, 5, between the top of the oil reservoir and the high pressure side of the circulating system; and a hand valve-controlled connection V⁴, 10, between the top 115 of the oil reservoir and the low pressure side of the system, connection 10 leading to the low pressure side, precisely in the same way in which connection 5 leads to the high pressure side. The reservoir is also provided with a sight gage 11 for indicating the level 120 125 130

of the oil in the reservoir. Oil from the reservoir fills the connection between the reservoir and the clearance chamber as well as that portion of the interior of said chamber 5 back of the clearance piston. The filling connection V' is opened only when more oil is to be supplied to the reservoir; at other times it is closed.

When the plant is in operation with the 10 clearance piston adjusted to give the auxiliary clearance required, the connection V^2 between the oil reservoir and the clearance chamber is closed and the reservoir and its high pressure and low pressure connections 15 have no effect upon the operation of the clearance device-proper. The low pressure valve V^4 also is closed; but the high pressure valve V^3 is open, thus subjecting the oil in the reservoir to pressure from the 20 high pressure side of the system.

When, however, while the system is in operation, it is desired for any reason to make a different adjustment of the clearance piston for the purpose of increasing 25 or decreasing the clearance in the auxiliary clearance chamber, the valve V^2 between the reservoir and the clearance chamber is opened with the effect of balancing the pressure on the clearance piston and permitting 30 its ready and safe adjustment, by means of its adjusting rod L and operating hand wheel W . After the auxiliary clearance has thus been adjusted, the valve V^2 between the clearance chamber and oil reservoir is again 35 closed and the operation goes on as before. Thus the only balancing done by the oil is during the periods when an adjustment of the clearance is being made in the clearance chamber.

40 The low pressure connection V^4 , 10—which is a nicety rather than a necessity—is provided as a convenient means for pumping out the gas from the reservoir whenever desired—as for example when it be- 45 comes necessary to replenish the charge of oil. In such case the high pressure valve V^3 should be closed and the low pressure valve V^4 opened, thus permitting the gas to be pumped out of the reservoir through 50 its connection 10 with the low pressure or suction side of the system. The reservoir can then be refilled with oil through the valve-controlled filling connection, after 55 which the low pressure valve V^4 can be closed and the high pressure valve reopened.

Manifestly the form and structural details of the embodiment of my invention can be widely varied without departure from the spirit of my invention; I do not 60 limit my claims therefore to the structural details hereinbefore shown and set forth in

the illustration of my invention but having described my invention and the best way now known to me of carrying the same into practical effect what I claim as new and 65 desire to secure by Letters Patent is—

1. In a closed refrigeration or ice making system of the compression type, the combination with the compressor and its connections with the high pressure and low pressure sides of said system respectively, of an auxiliary clearance chamber communicating with the interior of the compressor cylinder on the compression side of the piston therein, and means by which the clearance in said auxiliary clearance chamber, and consequently the clearance in the compressor as a whole, may be increased or decreased, whereby the capacity of the compressor can, without changing its speed, be 80 varied to conform to the fluctuations in the work to be done.

2. In combination with the elements of the combination specified in the preceding claim, manually operated means, independent of the means for regulating the volumetric capacity of the auxiliary clearance chamber, for opening and closing communication between said chamber and the interior of the compressor cylinder.

3. The combination of the elements specified in claim 1, when the means for varying the clearance in the auxiliary clearance chamber comprise a piston and operating stem and handle, as described.

4. In combination with the elements of the combination specified in claim 3, a valve-controlled connection between the circulating system on the discharge or high pressure side of the compressor and the auxiliary clearance chamber on the side of the piston therein opposite that on which the said chamber communicates with the compressor cylinder.

5. In combination with the elements of the combination specified in claim 3, an oil reservoir, a valve-controlled connection between the same and the head of the clearance chamber on the side of the piston therein opposite that on which the clearance chamber communicates with the compressor cylinder, and a valve-controlled connection between the oil reservoir, above the level of the oil therein, and the high pressure side of the system.

6. In combination with the elements of the combination specified in claim 5, a valve-controlled connection between the low pressure side of the system and the oil reservoir above the level of the oil therein.

In testimony whereof I affix my signature.

THOMAS SHIPLEY.
